CONTROL SYSTEM

John R. Boykin, Baltimore, Md., assignor to Westinghouse Electric Corporation, East Pittsburgh, Pa., a corporation of Pennsylvania

Application June 30, 1944, Serial No. 542,981

1 Claim. (Cl. 250—36)

1

My invention relates to oscillation generator systems and in particular relates to such systems employing electrical discharge tubes and in which it is desirable to be able to adjust the value of the power output over substantial range.

Oscillation generators of the electrical discharge tube type generally employing tunable circuits can have the value of their power output regulated to a desired value, in accordance with methods now prevalent in the art, either by (1) varying the filament voltage, (2) tuning the load circuit, or (3) changing taps on an output transformer or coil. Methods (1) and (2) are, however, limited in the range of variation which can be produced under practical circumstances by their employment, and method (3) only permits variations in steps of substantial magnitude rather than by continuous variation.

It is accordingly one object of my invention to provide an oscillation generator, to be employed, for example, in induction heating service, of which the magnitude of power output may be varied gradually over a wide range.

It is another object of my invention to provide an oscillation generator system in which the power output may be varied over a very substantial range and which shall be low in first cost.

It is a still further object of my invention to provide an oscillation generator system in which the output power may be varied by substantially infinitesimal steps over a wide range and which shall require only relatively small and compact control elements for this purpose.

It is still another object of my invention to produce an oscillation generator system for supplying power in which the magnitude of the output power may be gradually varied over a wide range without substantially varying the output frequency.

Still another object of my invention is to provide an oscillation generator system particularly adapted for use in the induction heating field in which the power output may be varied at will over a wide range gradually and without the intervention of steps of finite magnitude.

Other objects of my invention will become apparent upon reading the following description taken in connection with the drawing in which the single figure is a schematic diagram of the circuits of an oscillation generator and its control means embodying the principles of my invention.

Referring in detail to the drawing, an oscillation generator 1, which may be of any suitable type conventional in the art comprising an elec-

2

trical discharge tube having a control electrode, has its plate circuit fed from the positive terminal 2 of a source of high voltage through the primary 3 of an output transformer having a secondary winding 4 adapted to connect to any desired load such, for example, as an induction heating device. A winding 5 connected between the control electrode and the cathode of the tube 1 through a capacitor 6 is inductively related to the primary winding 3 and is shunted by a capacitor 7. A capacitor 10 shunts the primary winding 3. The cathode of tube 1 is connected to the negative terminal of the source 2 by way of ground. The arrangement so far discussed will be recognized as a conventional type of oscillation generator circuit.

In the prior art such an oscillation generator has customarily been operated with output power continuously flowing throughout the period in which it is desired to heat the load or otherwise supply it with power. In contrast to this, in accordance with my invention I impress on the control electrode of the tube 1 a control voltage consisting of substantially square-topped waves separated from each other by intervals in which the voltage of the control electrode falls to such a low value that the tube 1 is no longer able to continue in oscillation and its power output falls to zero. These voltage pulses are derived from the control tubes 8 and 9 by way of the keying tube 11, all of which I am about to describe in detail. By varying the relative length of the square-topped voltage pulse above mentioned to the intervals of zero voltage intervening between them, it is possible to vary the fraction of the time during which the generator 1 supplies substantial power to the load connected to output winding 4 over substantially any desired range, and correspondingly to vary the power supplied to the load through winding 4 from zero to 100% of the maximum power which the tube 1 is capable of generating. Since the periodicity of the square-topped pulses above mentioned can be made to have substantially any value over a wide range, the switching on and off of power from the oscillator 1 may take place with a high degree of rapidity. Furthermore, the ratio of the width of the square-topped pulse to the intervals between pulses may be varied with practically infinitesimal gradations, so that it is correspondingly possible to vary the power output of the generator 1 in substantially infinitesimal amounts.

Referring in detail to tubes 8 and 9, the former 55 has its anode fed from the positive terminal 12 of

a suitable direct-current source through a resistor 13. The tube 9 may be fed from the same source through a resistor 14, the negative terminal of the source being grounded. The cathodes of the tubes 8 and 9 are connected together and grounded through a resistor 15. The cathode of the tube 9 is likewise connected to the positive terminal 12 through a resistor 16. The control electrode of tube 8 is connected through a capacitor 17 to the anode of the tube 9, and the control electrode of the tube 9 is connected to the anode of the tube 8 through a capacitor 18. A resistor 19 is connected between the grid of the tube 8 and the grid of the tube 9, and is provided with a 10 slideable contact 21 which is connected to ground.

The above-described circuit connections for the tubes 8 and 9 make them act as a generator of square-topped periodic waves separated from each other by intervals of substantial zero voltage and the fraction of the wave period over which the square voltage pulse extends can be varied at will by moving the contact 21 along the resistor 19.

While I have described the resistor 19 and variable tap 21 as a specific means for varying the fraction of the wave period over which the square voltage pulse extends, it should be recognized that any alternative method of varying the ratio of the effective resistances between the ground and the control electrodes of tubes 8 and 9 may be substituted therefor.

The anode of the tube 8 is connected to the control electrode of a keying tube 11 of which the anode is connected to ground. The cathode of the tube 11 is connected through a resistor 22 to its control electrode and is likewise connected through a resistor 23 to the common terminal of the capacitors 6 and 7. As a result of this arrangement, positive voltage pulses are impressed through the tube 11 at intervals on the control electrode of the tube 4, and cause the latter to produce oscillations and supply power to the load connected to the terminals of winding 4 as long as the positive voltage pulse lasts. Thereafter the voltage impressed by the keying tube 11 on the electrode of tube 4 falls to such a low value as to cause the oscillation generator 4 to go out of oscillation and to cease to supply substantial power to the load connected to winding 4. This condition continues to the end of the period of the pulse generator 8, 9 whereupon the generation of a new positive pulse by the latter sets the os-

cillator 1 into oscillation again and the above described cycle is repeated indefinitely at the periodicity of the pulse generator 8, 9.

While I have described a particular form of 5 pulse generator for impressing the square-topped voltage waves on the control load of tube 4, it will be recognized that any known arrangement for impulsing such square-topped pulses may be substituted therefor.

I claim as my invention:

In combination with an electrical discharge tube having an anode circuit, a control electrode circuit comprising an impedance in series with means coacting with said anode circuit to cause 15 said tube to generate electrical oscillations, a generator of square-topped waves, a pair of resistors serially connected between the end of said impedance remote from the cathode of said electrical discharge tube and a point on the output circuit of said generator of square-topped waves, a second electrical discharge tube having an anode, a cathode and a control electrode, a connection between the last mentioned control electrode and said point, a connection between the cathode of said second electrical discharge tube and the common junction of said two resistors, and a connection from the cathode of the first-mentioned electrical discharge tube and the anode of said second electrical discharge tube, and to a variable tap on the output circuit of said generator of square-topped waves.

JOHN R. BOYKIN.
